UNITED STATES PATENT OFFICE

2,570,489

COMPARATOR

Norris S. Ryder, Chicago, Ill.

Application January 5, 1946, Serial No. 639,261

2 Claims. (CL 40—95)

1

My invention relates to comparators, in which a chart is mounted on rollers adapted to be wound on one roller, or unwound therefrom, the chart being supported or mounted on a pair of rollers oppositely disposed in parallel relationship, the ends of the chart being secured to the said rollers, and means being provided for automatically engaging one roller, while simultaneously providing a frictional drag on the other roller so as to permit winding without causing slack and permitting the maintenance of the said chart always in a taut condition, during the winding operation.

Another object of my invention is to provide a mechanism of the aforementioned character, which is instantaneously reversible causing the unwinding roller to be rewound, while simultaneously offering a drag check on the roller which had been wound and is subsequently being unwound, so as to permit the chart to be wound on one roller and unwound on the opposite roller and vice versa.

Another object of my invention is to provide a chart holding or retaining case with the roller mechanism heretofore mentioned, the said case being angularly adjustable so as to bring the viewing aperture thereof in any of various angular positions most convenient for an observer.

A further object of my invention is to provide in a chart holding means of the aforementioned character, a relator template, or secondary comparing chart, provided with apertures for alignment with the respective indicia or data on the major chart, producing or furnishing a relationship between indicia on the said secondary, or relator chart, comparatively associated with the indicia on the said major, or primary chart.

A still further object of my invention is to provide optical magnification means for enlarging the indicia of the said chart and relator chart, in proper focus to be readily viewed there-thru.

A still further object of my invention is to provide a comparator device of the aforementioned character which is provided with a stage having a light transmitting aperture therein, and lighting means associated therewith in order to cause light waves to be transmitted through the said major chart, as well as through the apertures in the said relator chart.

A still further object of my invention is to provide a comparator instrumentality of the aforementioned character, which is simple in construction, readily adjustable angularly with respect to the base thereof, being also provided

2

with means for indexing the various indicia on the chart thereon, both the major or primary chart, and the relator or secondary chart, to permit of various permutations and combinations of information contained on the said charts being related in close proximity enabling an observer to selectively obtain the related data therefrom. The said device being of a simple elemental structure, practical, and of such arrangement and assembly as to warrant economical production thereof in quantity manufacture.

Other features, objects, and ancillary advantages inherent in my invention will become apparent from an examination of the accompanying drawings, conveying further elucidation throughout the ensuing description, wherein like symbols are used to designate like parts, and in which:

Fig. 1 is a top elevational view of my invention.

Fig. 2 is a front view of my invention with certain portions thereof broken away, sectionally, so as to more clearly elucidate the general arrangement on the line 2—2 of Figure 4.

Fig. 3 is a fragmentary, transversal, cross-sectional, view taken, substantially, on the line 3—3 of Figure 2.

Fig. 4 is a transversal sectional view taken substantially, on the line 4—4 of Figure 2.

Fig. 5 is a staggered sectional view showing the fragmentary portion embracing the alternate frictional drive and frictional drag mechanism of my invention, incorporated as an important feature of my invention, the view being taken, substantially, on the line 5—5 of Figure 4.

Fig. 6 is an end sectional view, similar to Figure 4, showing a slightly modified construction of my invention.

Fig. 7 is an enlarged fragmentary detailed view of the manipulating mechanism for operating the relator or secondary chart.

Fig. 8 is an end view of Figure 7, and;

Fig. 9 is a fragmentary view looking substantially in the direction 9—9 of Figure 6.

Referring to Figures 1 to 5, one form of my invention illustrates a device on which a chart may be mounted, by virtue of oppositely disposed parallel roller supports, and manipulating means for winding alternately the said chart on either of the said parallel rollers while simultaneously unwinding the chart from the opposite roller.

My invention is, generally, designated 10, and consists of a base 11 on which are mounted the brackets 13, having suitable web portions connecting the extremity bearing portions 12 there-

of, which are suitably bushed with bushings 14, in which on one hand is attached the manipulator or knob 17 pinned by fastening 16 to a shaft 15, connected through the end supports 30 by suitable lock washers 20 and lock nuts 19, thus confining the same in position for rotation of the said shaft 15 within the bushing 14.

The body 23 is made of suitable sheet metal material and is mounted over the end drums 24, over which the sheet metal body 23 is enveloped and secured to the top by suitable rivets 40, or other similar fastening means, the said fastening means simultaneously securing an inner cage 25 by virtue of its end plate reinforcements 30 and 31 associated with the cage 25. To the inner portion of the cage 25, I secure the supporting brackets 28 having their bases 26 secured by screws or rivets 27, the said brackets being of a formation as shown in Figure 3 and being arcuately cut-out as indicated at 44, and reinforced with ribbing 44'. The cut-out portions 44 are clearances for the chart supporting shafts or mandrels 34, which are made of suitable lengths of tubing secured to the stub shafts 33 and 39 and provided with spool-like flanges 31 and 38 so as to confine rotatably therebetween the edges of the chart which is to be wound thereon. The mandrels 34 are provided with suitable collars 35 secured through pins 36, securing the mandrels 34 to the collars 35, and to the stub-shafts 33 and 39, the stub-shaft 39 being extended to work through the bushing 40, rotatably, on which the indexing frictional feed and drag mechanism is mounted, and more clearly elucidated in Figures 4 and 5.

In Figure 2, at the extreme right, I provide a knob 67, which is threadably engaged to a stub shaft 68, operating in the bushing 14 of the bracket 12, and being extended inwardly so as to be integrally secured to the pinion 69 in meshing engagement with another pinion gear 69' and which is secured to the end reinforcement plate 31, having a guide bushing 32 therein, so that rotation of the knob 67 will cause the meshing relationship of gears 69 and 69' to cause the body 23 to be angularly adjusted, and to be rotated with respect to the base, causing the viewing lens element 41 thereof, to be set in a position toward, or away, from an observer who would be positioned to the left or the right of Figure 4. The brackets 13 are secured to the base 11 by virtue of cap screws 21, the base being suitably counter-bored, as at 22, in order to offer a smooth bottom portion to the base, that it may be positioned on any flat, or level, surface for support.

The frictional drag mechanism is best illustrated in Figures 4 and 5, where it can be seen, that I provide the shaft 15, to which I secure the gear 63, which is in meshing relationship with a gear of like diameter designated 53, and mounted on a stub-shaft 57, having reduced ends peened over at 58, and 59, to links 55, so as to confine the gears 53 and 63 in a pivotal assemblage. The gears 53 and 63 are each provided with extended shoulder portions, or hub portions 60, and are of the angular and tapered formation, indicated at 53 and 54 for purposes to be more clearly elucidated.

The shafts 39 have rotatably secured thereto the hubs 56 to which are anchored the friction plates 49 at 56 on the enlarged boss 48 of the hubs 50, the said plates having angular flared out formations as indicated at 52 in order to be configurative with the cross-sections 53 and 54

of the gears 53 and 63. The mating flange 61 is of the same formation as the one designated 49, with the exception that it is bored and mounted, slidably, on the hub 50, and urged in contacting relationship with the flange 40, so that its similarly flared out portions 51 will tend to, frictionally, engage the gears 53 and 63, the spring 47 providing the frictional action. The said spring 47 is confined in place by a cup-shaped washer element 46, which is pinned to the shaft 39, by virtue of pin, or key 45. Thus it can be seen that the flanges 61 are urged in frictional contacting relationship to confine the toothed sections of the gears 53 and 63; the flange 62 being likewise retained in frictional engagement with said gears.

The operation of this unit is rather simple. When the knob 17, which is connected to the shaft 15, is rotated in the direction of the arrow, the very first thing that will occur, will be that the linkage will tend to veer over to the left, thus causing the gear 53 to motivate the frictionally engaged unit 51, causing the same to wind the chart 65 which is trained over the idler rollers 29 so as to present the portion 66 thereof to be viewed through the lens 41. The said chart is trained over the rollers 29, and connected through the connecting portions 65 and 64 to the mandrels 34. While the linkage has been veered over to the left, the lower gear 63 also furnishes a frictional drag of the unwinding unit 62, so as not to cause an "over-winding" and wrinkling of the chart that is confined on the mandrels 34; likewise, when the rotation of the knob 17 is reversed the linkage will veer to the right causing the winding spool 62 to be frictionally engaged by the gear 53 causing the same to be wound, while simultaneously the gear 63 offering a frictional gear drag to the winding spool 61 completely reversing the operation. Thus it may be seen that the chart can be readily wound and unwound by rotating the knob 17 in either direction.

The lens is, preferably, secured by means of the top plate 106, which tends to bind together the enveloped body 23, and the inner cage 25 holding everything securely by virtue of fastenings 40, which is also provided with means to retain the convex lens 41 in proper focus for magnification purposes, the same being retained by suitable gibs 42, which are of angular formation and are removably held in place by screws 43 so as to permit removing the lens when that should be necessary. Thus assuming that we have a chart mounted on the mandrels 34, and it is desired to bring a portion 66 thereof in visual alignment through the lens 41, that operation can be effectuated by the means heretofore related i. e. by operating the control knob 17 either in clock-wise or counterclock-wise direction, depending on which part of the chart the information is contained, and bringing the same to view as at 66, on the viewing stage where it may be viewed and notations or observations taken or recorded.

In some instances it may be desirable, or preferable, to have a chart indexing means, supplemented with an auxiliary relator chart, or template chart, or secondary chart, working in concert therewith, in which event, I have slightly modified my invention as embraced in Figures 6, 7, 8 and 9, and in which I show, a body structure which is of slightly different shape, made of sheet metal material designated 70, and an inner cage structure 71, having top guiding lip portions 73, being held firmly in place by rivets securing also the flanges 74 of the lens support 75, in which

seated portions 76 are provided to retain the convex lens 77 at the proper focal distance from the viewing stage where the portion 66 of the major chart is to be viewed in connection with the relator chart 81. The relator chart 81 is trained over idlers 80 and secured to hollow tubular mandrels 98, having slotted portions 99 therein, and having suitable shoulder portions so as to urge them against the contact plates 105 in frictional engagement by virtue of the resilient washers 94, each having a series of finger portions 95 spaced by cut outs 96, and arcuately shaped or dished out as indicated at 93 in order to permit smooth operation of the stub-shaft 100 connected to the manipulating knob 101, so that the same, when rotated in either clock-wise or counter-clock-wise directions, will wind, and unwind from the oppositely disposed rollers 98 respectively. Thus the washers 94 offer frictional resistance to the shoulders 97 of the mandrels 98 preventing the same from acquiring momentum during rotation.

The relator chart 81 is trained over the rollers 80 and the portions 79 at the ends thereof are connected to the tubular retainers 98. It may be desirable, as indicated in this particular instance, to have the inner case 71 arcuately bent as at 83, and angularly bent upwardly, to form a supporting ledge 82 on which the support 85 is secured by means of rivets or other securing means 84 so as to provide a supporting platform for the bracket supporting the idlers 29, and also for supporting the insulated structure plate 86, for supporting a series of electric sockets 90, substantially secured in place by means of the lock-nuts 89, and being held firmly by a plate 87, having bent portions 88 suitably secured to the angularly bent portions of the cage 71. It is the province of the sockets 90 to support removably a series of lamp bulbs 91, connected to a duplex wire connection 92, which may be plugged into any electric light source of energy.

It is to be stressed, that the major chart wound on the mandrels 34 is made of a transparent material, such as Celluloid, and has certain information imprinted thereon. The relator chart 79 however, is made of an opaque material and has in one continuous line a series of elliptical openings 102, so as to register with certain indicia, or information, on the chart 66, the relator chart also having a series of relator figures 104 which are to be related with respect to the figures selectively sought out on the major chart, the said figures being designated 103. Thus the major chart being transparent, may be indexed so that one row, or line of figures, or other information thereon, will be clearly visible through the aperture confined between the figures 78, permitting the light emitted by the bulb 91 to be transmitted through openings 73 in the supporting stage 72, so that the light will aid, visually, and optically through the lens 77, the observer to obtain a clear view of the informational data contained on the major chart, through the displayed portion 66 thereof.

The secondary chart or relator chart may be provided with as many alternate series of elliptical openings 102 as desired, each of sufficient magnitude to embrace the numerical data 103 imprinted on the major chart, or other data printed on the major chart, and directly below the said openings 102, a series of related figures or informational data.

My device may be used for computations, and the relation of computed values, or the relativity figures which have been established or computed.

Altho, I have herein described rather succinctly the construction of my invention, and inasmuch as the same is susceptible of modifications and improvements, I hereby reserve the right to all modifications and improvements coming within the scope and spirit of my invention, as well as any modifications embraced in the accompanying drawings, and also all those modifications falling within the purview of the foregoing disclosure.

Having thus described and revealed my invention, what I claim as novel, and desire to secure by Letters Patent, is:

1. A device of the class and for the purposes described comprising a support, a body secured thereto and providing a viewing aperture along the top portion thereof, chart winding and unwinding mandrels rotatably secured to the body, a supporting plate carried by the body below the aperture, a chart mounted on said mandrels and trained over said supporting plate, other chart winding and unwinding mandrels rotatably supported in said body, a second chart mounted on said other mandrels and trained over said first chart over said supporting plate, said second chart having a plurality of elliptical openings formed therein adapted to register with indicia on said first chart, said supporting plate having an elliptical opening therein adapted for registration with the elliptical openings formed in said first chart, and illuminating means within said body beneath said supporting plate.

2. A device of the class and for the purposes described comprising a body providing in a wall thereof a viewing aperture, chart winding and unwinding mandrels rotatably supported in said body, a supporting plate mounted below said aperture, a transparent chart mounted on said mandrels and trained over said supporting plate, other chart winding and unwinding mandrels rotatably supported in said body, an opaque chart mounted on said other mandrels and trained over said transparent chart, said opaque chart having a plurality of elliptical openings formed therein adapted to register with indicia on said transparent chart, said supporting plate having an opening formed therein adapted for registration with the openings of said opaque chart, and illuminating means within said body beneath said supporting plate.

NORRIS S. RYDER.
